UNITED STATES PATENT OFFICE.

HUGH V. BUTT, OF NORFOLK, VIRGINIA.

DUMP-SCOW.

1,399,048.

Specification of Letters Patent.

Patented Dec. 6, 1921.

Application filed March 3, 1921. Serial No. 449,440.

To all whom it may concern:

Be it known that I, HUGH V. BUTT, a citizen of the United States, residing at Norfolk, in the county of Norfolk and State of Virginia, have invented certain new and useful Improvements in Dump-Scows, of which the following is a specification.

My invention relates to dump scows or vessels.

10 The object of the invention is to provide a dump or cargo scow which may be unsinkable and adapted for any kind of cargo such as mud brought up by dredges, coal, water, sand and other material and capable of being easily and quickly dumped and cleaned.

Further objects and advantages will be more fully described herein and specifically pointed out in the claims hereunto annexed recourse being had to the accompanying drawings forming a part of this specification in which:

Figure 1 is a plan of one end of a scow or floating vessel equipped with my apparatus.

Fig. 2 is a longitudinal section of one end 25 of a scow showing end views of two of the cylindrical dumping bins or hoppers.

Fig. 3 is an enlarged end view of one bin or hopper and a section of the scow.

Fig. 4 is a part longitudinal section of one 30 of the dump hoppers.

Fig. 5 is a side view of the hopper rotating or dumping apparatus, and

Fig. 6 is an end view taken on the line 1—2 in Fig. 5.

35 In the drawings like reference numerals indicate similar parts in all the several views:

1 is the scow, barge or float which is built to accommodate the hereinafter described 40 mechanism or an ordinary scow in use may be altered to receive the same, as desired.

2 represents the top surface or deck of the scow or float and 3 are water tight compartments or partitions extending, preferably, athwart the scow or vessel, and by them are formed the vertical dump wells 4 reaching from the deck 2 through to the bottom of the scow and consequently below the water line 3^a, as shown in Fig. 2.

50 Over and partly within the wells 4, are placed the outer bearing and supporting rings 5 arranged crosswise over the wells or openings and are disposed in an upright position near each end thereof, as shown,

and held in place by the hereinafter described brackets.

The rings 5 are channel shaped in cross section and contain rollers 6 mounted for rotation upon the pins or axles 7, 8, Fig. 4, are the middle supporting rings having rollers 9 upon the axles 10 and are for the purpose of supporting the center of the bins or hoppers 14 and may be more than one, depending on the length of the same.

Both the rings 5 and 8 are held to the deck 65 2 of the scow by means of the bolts 12 passing through the lower flange of the brackets 11 which are in turn riveted or bolted to the rings 5 and 8.

In Fig. 4, 13 is a segmental plate or ring 70 member forming, with the other ring elements, a channel and is for the purpose of removing the rollers 6 by taking off the plate and a similar arrangement may be resorted to in regard to the middle rings 8, 75 as desired.

The dumping cylinders, hoppers or bins 14 are usually made of plate steel or iron and have ends 15 and an open side 16, above the axis or horizontal center line thereof so 80 that the end members 15 have the form of a circular plate with a segmental portion removed, as shown.

17 are channels formed into rings and are bolted to each end of the circular hoppers or 85 bins 14 to form a track for the rollers 6.

As shown, the rollers 9 in the channel ring 8 bear directly upon the plates of the cylindrical bins or in any other convenient manner.

90 As an additional support for the bins 14, I may use a short axle 18 working in a suitable bearing 19, Fig. 1, also a short axle 20 on the opposite end of the cylinders 14 and secured by a flange to the bin end members 95 15 and held for rotation by a bearing stand 21 of any convenient height from the deck 2 and the said height will govern the distance of the opening or bin outlet 16 from the deck surface and may be flush therewith 100 or above the same, as shown in Figs. 3, 5 and 6.

On the shaft or axle 20, and outside of the bearing stand 21, there is placed a bevel or miter gear wheel 22 normally in mesh with 105 the slideable bevel or miter gear 23.

The gear wheel 23 is provided with a sleeve or axial extension 24 furnished with a key-

way partly cut in the sleeve and the shaft 25 for the key or feather 26 so that it may slide a short distance either to the right or left upon the main horizontal shaft 25 which extends to any length according to the number of bins or hoppers that the scow contains which is usually about six, though any number may be used as desired.

The sleeve 24 is provided with a suitable 10 circumferential slot into which there is loosely fitted a ring 27.

The ring is provided with a pin 29 which is in turn placed upon the lever 28 having a fulcrum block 30 fastened to the deck 2 and 15 by which the gear wheel 23 may be placed in and out of engagement with the gear wheel 22 so that any one or all of the bins or hoppers may be dumped, as desired.

The shaft 25 is suitably supported at both 20 of its ends, one of the supports is an ordinary bearing, (not shown), and the other by the gear frame or housing 32, as shown in Fig. 5.

The left hand end of the shaft 25 is provided with a gear wheel 31 meshing with a pinion 33 on the shaft 34 which in turn carries the gear wheel 35 meshing with the drive pinion 36 on the shaft 37 and upon said shaft is a hand wheel 38 on the outside 30 of the frame or housing 32 by which power is multiplied when operated allowing one or more of the cylindrical bins to be rotated so as to dump their contents, as in the case with mud excavated by dredges or any other 35 material that is desired to dump overboard.

39, represented by dotted lines in Figs. 3 and 6, indicates a combing which may be placed around the bins 14 to prevent the wash of water when the scow is loaded heavily or is in a rough sea.

If it is desired to dump the load of the bins, for example, sand or ballast, upon the shore, the entire bins with the rings 5 and 8 may be lifted out by a derrick or crane by 45 means of the slings 41 attached to the eyes or rings 40 secured to the upper part of the rings 5 in any suitable manner.

In order to lift the cylinders or bins 14 from the wells in this manner, it is only 50 necessary to remove the bolts 12 from the bracket supports 11, Fig. 3, and the caps of the boxes 19 and 21 when the gear wheel 22 is out of mesh with the bevel gear 23.

I may use other gear means for rotating 55 the cylinders or bins 14, for example, the providing of segmental racks near or upon

the rings 8 meshing with a spur gear wheel on the shaft 25 instead of the bevel gears, as shown.

Various changes can be made in the mechanical construction to suit working conditions and requirements for which the invention is used.

It will be seen that the bins or hoppers 14 act in themselves as independent buoyant 65 means and though the scow or vessel may be stove in by a collision the same would be prevented from sinking by the flotation of the cylindrical bins or hoppers.

The invention is therefore valuable on account of the impossibility of its sinking more particularly if the open sides or outlets 16 of the bins 14 are covered by any suitable means.

By my apparatus, marine insurance rates 75 would be decreased as the danger of the loss of valuable cargoes would be very much lessened.

Another advantage of my invention is that the bins may be used for a variety of 80 cargoes, for instance, coal may be transported on one trip, unloaded, the bins washed out, rinsed and dumped and when dry may be reloaded with salt, mixed freight, sand &c., on the return trip, then used for mud 85 dredged up by mud machines or dredges, again washed and dumped and used for any kind of cargo.

I claim:

1. A scow having vertical dump wells opening 90 through the bottom, bearing rings disposed partly within the wells and partly above the same, and cargo cylinders rotatively mounted within said rings.

2. The combination with a scow having a 95 series of wells extending therethrough from the deck to the bottom, of cylindrical cargo bins placed over and partly within said wells, gear means on said cylinders for rotating the same, a horizontal shaft having 100 gear means thereon adapted to normally mesh with the first named gears, and lever operated means for disconnecting said gear-ing.

In testimony whereof I have hereunto 105 affixed my signature in the presence of two witnesses.

HUGH V. BUTT.
